UNITED STATES PATENT OFFICE.

WILLIAM RILEY CROW, OF BUFFALO, ASSIGNOR TO HIMSELF AND EDWARD R. ULRICH, JR., OF SPRINGFIELD, ILLINOIS.

CONVEYER.

SPECIFICATION forming part of Letters Patent No. 412,949, dated October 15, 1889.

Application filed February 1, 1889. Serial No. 298,331. (No model.)

To all whom it may concern:

Be it known that I, WILLIAM RILEY CROW, of Buffalo, in the county of Sangamon and State of Illinois, have invented a new and 5 Improved Conveyer, of which the following is a full, clear, and exact description.

This invention relates to conveyers, the object of the invention being to provide a conveyer by means of which heavy material— 10 such as corn on the cob, grain, ores, or any other material—may be elevated and delivered to a chute; and to the end named the invention consists in the construction and arrangements of parts, all as will be hereinafter fully 15 described, and specifically pointed out in the claim.

Reference is to be had to the accompanying drawings forming a part of this specification, in which similar figures and letters of reference 20 indicate corresponding parts in all the views.

Figure 1 is a central longitudinal sectional elevation of my improved conveyer. Fig. 2 is a cross-sectional elevation taken on line 25 $\alpha\alpha$ of Fig. 1, and Fig. 3 is a similar view of a modification of the elevator.

In the drawings above referred to I have 30 illustrated my conveyer as it would appear when arranged in connection with a corn-sheller.

In the construction shown, 10 is a receiving-case having an upwardly-extending floor-section 11, which leads to a delivery-chute 12. The receiving-case 10 may be arranged beneath 35 a crib having a movable trap or floor, or otherwise in position to receive the material to be transferred. Near the bottom of the case 10, I mount two transverse shafts 15 and 16, and these shafts carry wheels or pulleys, as 17 and 18, the wheels 17 being near that end of the case which is opposite the end from which the chute extends, while the wheels 18 ride directly above the point from which the inclined section 11 springs. With- 40 in the case 10 and near the chute 12 there is a third shaft 19, which carries sprocket-wheels 20, and a driving-pulley, the position of which is indicated by dotted lines. Upon

the pulley or wheels and the sprocket-wheels that are arranged as above described I mount 50 chains 30 and 40; and in practice I prefer that these chains be guided by wheels 21, that are carried by a transverse shaft 22, so mounted that the chains will extend at an angle of about forty degrees in passing from 55 the wheels 21 to the wheels 17. The chains 30 and 40 are provided with a number of flights 23, the extending edges of which flights as they advance bear closely against the flooring of the case 10. 60

In connection with the conveyer there is arranged a corn-sheller 50, and in the construction shown in the drawings the belt which drives the shaft 19 is driven from a shaft controlled by the corn-sheller mechanism. To prevent the clogging of the belt and to hold the flights against the bottom of the case, I provide shields 25 and 26, said shields being placed as clearly shown in the drawings and secured to the side walls of the 70 case 10.

In the modification shown in Fig. 3 the shafts 15, 16, 19, and 22 carry each a single wheel or pulley centrally arranged thereon, around which a single belt 30^a passes, to 75 which belt the flights 23 are attached at the center, and a single shield extends centrally of the case above the belt, the connection and operation being otherwise the same.

In operation, the material to be delivered 80 to the chute is fed to the case 10 at any convenient point between the carrier-belts when the conveyer is made up of the chains 30 and 40 and the flights carried thereby, and each side of the belt when a single belt is used, 85 and this belt is started forward in the direction of the arrow shown in connection therewith in Fig. 1, the material being gathered by the flights and carried forward and upward into the chute, the amount of material 90 delivered to the chute depending upon the speed at which the belt is driven.

Having thus described my invention, I claim as new and desire to secure by Letters Patent—

The herein-described conveyer, consisting 95 in the casing 10, having a discharge-chute 12

and an upwardly-inclined floor-section 11, wheel 20 at the upper end of said section, wheel 18 at the lower end, lower and upper wheels 17 and 22 at the opposite end of the 5 casing, the wheel 22 being in advance of the wheel 17, a shield between wheels 17 18, an inclined shield between wheels 18 19, and the

endless chain passing around said wheels and under the shields provided with transverse flights or blades 23, substantially as set forth. 10

WILLIAM RILEY CROW.
